A. J. CHEVRETTE

WEFT DETECTOR ON LOOM TRANSFERRER

Filed Dec. 27, 1926

UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR ON LOOM TRANSFERRER.

Application filed December 27, 1926. Serial No. 157,047.

This invention relates to improvements in weft detectors more particularly of the type to be located in regularly moving transerrer arms for weft replenishing looms and it is a general object of the invention to provide a detector which shall cooperate with a bobbin to give proper indication of weft exhaustion independently of the conical form of the yarn on the bobbin.

10 In patent to Ryon #1,372,316, there is shown a transerrer arm having a detector thereon, both of these elements being moved downwardly toward the shuttle when the latter is on the magazine side of the loom. 15 Detectors of this type have heretofore been made with a side slipping yarn engaging member made to move either toward or away from the bobbin butt. When moving toward the butt an indication is likely to be 20 given prematurely if the detector surface engages the conical part of the bobbin tapering toward the butt, and if the detector moves toward the tip of the bobbin a premature indication is likely to result when the 25 mass of yarn tapers toward the tip. It is an important object of my present invention to provide a detector having preferably a pair of oppositely moving detectors both of which must slide along the bobbin before indication 30 of weft exhaustion will be given.

The particular manner shown herein for actuating the detector mechanism to cause the same to move toward the bobbin makes use of the inertia of the moving mass of the 35 detector, a spring being provided to hold the detector normally in raised position so that it will be able to move downwardly toward the bobbin when the transerrer arm is brought to a sudden stop at the bottom of its 40 stroke. It is a further object of my invention to have the weft detectors disposed on opposite sides of the line along which the mass moves so that the pressure of the detectors may be equalized.

45 Detectors of the type specified herein are now made with a plunger normally held in retracted non-indicating position by a latch pivoted to the transerrer arm and having holding engagement with the plunger. As heretofore made the latch has had a vertical tail and at the time of indication the major component of this movement has been hori-

zontal. It is a still further object of my invention to extend this tail horizontally so that its major component at the time of indication will be vertical, thus permitting the 55 spring for the latch to help the detector in moving upwardly after indicating movements. This is desirable in view of the fact that on indicating beats of the loom the detector moves to a position lower than usual and there is, therefore, the possibility that the front wall of the shuttle will engage the detector on the backward stroke of the 60 lay.

65 It is a more particular object of the invention to have the detector carrier slidably mounted in the transerrer arm and held against angular movement by a trip which engages the plunger retaining latch.

70 With these and other objects which will appear as the description proceeds, my invention relates to the arrangements and combinations of parts hereinafter set forth, and more particularly pointed out in the claims.

75 In the accompanying drawings wherein a convenient embodiment of my invention is shown,

Fig. 1 is a vertical central section through that part of the transerrer arm which normally extends from the surface to be detected and showing the parts in non-indicating position with a sufficient supply of weft 80 present,

Fig. 2 is a view similar to Fig. 1 but with 85 insufficient supply of weft present and the detector moved to indicating position,

Fig. 3 is a fragmentary top plan view taken in the direction of arrow 3 of Fig. 2,

Fig. 4 is a horizontal section on line 4-4 90 of Fig. 2,

Fig. 5 is a detail vertical section on line 5-5 of Fig. 2, and

Fig. 6 is a fragmentary vertical section on line 6-6 of Fig. 1.

95 Referring to the drawings, a transerrer arm 10 has a bobbin engaging heel 11 and a yarn engaging tip 12. Vertical side walls 13 connecting said heel and tip define a vertical slot 14 across which extends pin 15. Pivoted on said pin is a latch 16 having a hook 17 normally holding head 18 of a plunger 19. Said plunger has an indicating end 20 which moves in a horizontal bore 21 of web 22 ex-

tending between the walls 13. A clip 23 secured to the transerrer arm partly closes the inner opening of bore 21 and a spring 24 interposed between the clip and the indicating portion tends to move said plunger outwardly from the position shown in Fig. 1 to that shown in Fig. 2. The latch which normally prevents this movement has a torsion spring 25 surrounding pin 15 and having one end thereof held by the transerrer arm as at 26 and the other end extending over a portion of the latch as at 27 to hold the latter in the position shown in Fig. 1.

On each detecting beat of the loom the transerrer arm is moved downwardly toward the surface to be detected, the plunger 19 remaining in non-indicating position when there is a sufficient supply of weft on the bobbin B and moving outwardly to the indicating position shown in Fig. 2 when there is an insufficient supply of weft on the bobbin. The matter thus far described is common with the exception of certain portions of the latch and forms no part of my present invention.

My improvements relate more particularly to the detector and a portion of the latch, and in carrying my invention into effect I provide the transerrer arm with an upwardly extending horn 40 having a cylindrical bore 41 therein. A plunger 42 is mounted in the bore for free vertical movement and may be flattened on one side thereon, as at 43, to have secured thereto the upper end of a trip 44 by means of a screw 45. Said trip has a horizontal portion which extends through slot 46 in the upper part of the horn, said slot communicating with the bore 41.

In order to hold the plunger 42 normally in raised position I provide the trip with a vertical portion 47 having a series of holes 49 therein one of which receives the left end of a wire spring 48. The right end of said wire is located between a pair of collars 50 which are clamped together by screw 51 passing into a portion of the transerrer arm. Said spring 48 can have the pressure exerted thereby varied by the turning of screw 50 or by inserting the left end thereof into one or another of the openings 49.

The lower end of the trip 44 is adapted for engagement with a horizontally extending tail 52 of the latch 16 and adjustment between the trip and the tail may be afforded by a slot 53 formed in the upper end of the trip through which the screw 45 extends. When making the vertical adjustment of the trip the wire 48 may be inserted into one or another of the openings 49 to give the correct pressure.

The yarn engaging portion of the detectors comprises a pair of substantially similar but oppositely moving detectors 60 each pivoted as at 61 to a plate 62 secured in the

lower end of plunger 42. The upper end of said plate is formed as stops 63 which may be hook-shaped to receive the upper ends of light tension springs 64 the lower ends of which are connected to the detectors as indicated in Figs. 1 and 2. The pivots 61 are spaced apart a distance substantially equal to the distance between the center of the yarn engaging toothed portions 65 of the detectors, although this relation is not necessary.

The upper end of each detector is bent back on itself so as to be U-shaped as shown in Fig. 4, each detector therefor having pivotal contact with its pivot 61 on both sides of the plate. As shown in Figs. 1 and 2 the downwardly extending portion of one detector is on the front of plate 62 while the corresponding portion of the other detector is in back of the plate. This makes it possible to use substantially similar detector elements without causing interference. The form of detector illustrated herein is set forth more particularly in my co-pending application Serial No. 154,407.

Under normal conditions the movable parts of the detector are held yieldingly in raised position by spring 48 and as the transerrer is brought to a sudden stop at the lower end of its stroke, the plunger 42 will slide downwardly in the bore 41 against the action of the spring to bring the detector 60 into contact with the yarn on the bobbin. As shown in Fig. 1, when sufficient yarn is present the detectors are held against angular movement around pivots 61 and the plunger 42 is arrested in its downward movement before the trip 44 can engage the tail 52 of the latch. The plunger 19 therefore remains in non-indicating position as the transerrer arm is raised and no indicating movement is given to the angular lever, not shown herein, but set forth in the aforesaid patent to Ryon. When insufficient weft is present however, the detectors slide along the denuded bobbin to the position shown in Fig. 2, thus permitting the plunger 42 to move downwardly far enough for the trip 44 to engage the tail 52 and raise the latch, compression spring 24 thereupon moving the plunger 19 to the indicating position shown in Fig. 2. At this time the plunger and parts carried thereby are lower than on non-indicating beats and it is therefore desirable to give them a quick upward movement in order that they may clear the front wall of the shuttle as the lay moves rearwardly. This result is accomplished in part by the spring 48 which normally performs this function and in part by the torsion spring 25 which, by engagement of the vertical portion 47 of the trip 44 with the latch helps to raise the plunger on indicating beats.

When released the head of the latch may engage the inner end of the indicating plunger 19

to prevent undue angular movement of the same in a clockwise direction as viewed in Fig. 1.

From the foregoing it will be seen that I have provided a detector having a pair of oppositely moving side slipping weft detectors mounted on a regularly moving transerrer arm to be presented to the weft each detecting beat of the loom. It is necessary for both detectors to slide along the bobbin before indication results, so that if a conical surface of yarn is presented to either detector such as normally to cause indication, the plunger 19 will not be released if the other detector is in contact with yarn. It will further be seen that the trip 44 moving in slot 46 holds the detectors in parallel alignment with the surface to be detected. Also, it will be seen that the latch 20 serves the purpose not only of controlling the indicating plunger but also exerts an upward force on the trip and detector mechanism when the latter is in its lower position and needs to be removed from the path 25 of the shuttle. Means are provided for varying the vertical position of the trip with respect to the plunger and provision is also made for a compensating adjustment between the trip and the spring 48.

Having thus described my invention it will be apparent that changes and modifications may be made therein by those skilled in the art without departing from the spirit and scope of the invention and I do not wish 35 to be limited to the details herein disclosed, but what I claim is:

1. In a weft detector mechanism for a loom having a transerrer arm movable on detecting beats of the loom toward a surface to be detected, a carrier slidably mounted on the transerrer arm in a direction toward and from the surface to be detected, a pair of detector elements pivoted to the carrier at spaced points, said elements being disposed diagonally with respect to each other and having weft engaging surfaces spaced with respect to the surface to be detected, and means to effect indication of weft exhaustion at such times only as both 50 detectors slide along the surface to be detected.

2. In a weft detector mechanism for a loom having a transerrer arm movable on

detecting beats of the loom toward a surface to be detected, a carrier movable on the transerrer arm toward and from the surface to be detected, detecting means on the carrier to prevent a complete movement of the latter when weft is present, said detector moving when weft is exhausted and said carrier having a complete movement toward the surface being detected, indicating means including a pivoted latch, a trip on the carrier, and an indicating element controlled by the latch, said trip being out of contact with the latch when weft is present but moving into engagement with the same by a movement toward the surface to be detected when the detector has an indicating movement and the carrier has a complete movement toward the surface being detected.

3. In a weft detector mechanism for a loom having a transerrer arm movable on detecting beats of the loom toward a surface to be detected, a carrier substantially cylindrical in cross section and slidable on the transerrer arm toward and from the surface to be detected, a pair of detecting elements having spaced weft engaging surfaces, and means to prevent angular movement of the carrier relatively to the transerrer arm to keep the weft engaging surfaces in proper alignment relatively to the surface being detected.

4. In a weft detector mechanism for a loom having a transerrer arm movable on detecting beats of the loom toward a surface to be detected, a carrier substantially cylindrical in cross section and slidably mounted on the transerrer arm toward and from the surface being detected, a pair of detecting elements mounted on the carrier and having spaced weft engaging surfaces, means to indicate weft exhaustion including a trip mounted on the carrier, and means fixed with respect to the transerrer arm to engage the trip and prevent angular movement thereof and of the carrier relatively to the transerrer arm, whereby the detecting surfaces are held in proper alignment with respect to the weft surface being detected.

In testimony whereof I have hereunto affixed my signature.

AUGUSTIN J. CHEVRETTE.
